UNITED STATES PATENT OFFICE.

JAMES K. DIAMOND, OF GRAND RAPIDS, MICHIGAN, ASSIGNOR TO CLIPPER BELT LACER COMPANY, OF GRAND RAPIDS, MICHIGAN.

BELT LACER.

Application filed March 30, 1925. Serial No. 19,479.

To all whom it may concern:

Be it known that I, JAMES K. DIAMOND, a citizen of the United States, residing at Grand Rapids, county of Kent, State of Michigan, have invented certain new and useful Improvements in Belt Lacers, of which the following is a specification.

This invention relates to improvements in belt lacers.

10 The main object of this invention is to provide an improved belt lacing hook which may be "set" into the belt in a very uniform manner.

15 Objects pertaining to details and economies of my improvements will definitely appear from the detailed description to follow.

I accomplish the objects of my invention by the devices and means described in the 20 following specification. The invention is clearly defined and pointed out in the claims.

A structure embodying the features of my invention is clearly illustrated in the accompanying drawing forming a part of this 25 application, in which:

Fig. I is a side view of one of my improved belt lacing hooks open.

Fig. II is a detail longitudinal section of 30 a belt lacing embodying my improved lacing hook.

Fig. III is a fragmentary transverse section on a line corresponding to line 3—3 of Fig. II, the hooks being shown in full lines 35 for convenience in illustration.

Fig. IV is a fragmentary section on a line corresponding to line 4—4 of Fig. II.

Fig. V is a detail view illustrating the 40 setting of the hook and some of the advantages of the hook in setting.

In the drawing similar numerals of reference refer to similar parts in all of the views, and the sectional views are taken looking in the direction of the little arrows 45 at the ends of the section lines.

Referring to the drawing, 1, 1 represent the belt sections to be joined, 2 the hooks set therein and 12 a coupling pin. My improved hook (I here use the term "hook" 50 as that is the name current in the trade for this class of devices) is preferably formed with arms 3 of unequal length. These arms diverge outwardly and are provided with parallel portions 4 at their outer ends terminating in prongs 5 disposed at right angles

to the parallel portions. The diverging portions of the arms 3 are preferably of the same length as in the embodiment illustrated.

In practice a plurality of these hooks are 60 simultaneously set into the belt, setting tools of different types adapted to close or force the hooks into the belt being provided.

In Fig. V, I illustrate a device for setting or applying the hooks which comprises a 65 holder 6 having slots 7 adapted to receive the hooks, the hooks being retained within the slots by the pin 8. The jaws 9 are carried by the pivoted arms 10, the jaws being mounted upon the arms for limited tilting 70 movement.

This device, with a plurality of hooks therein, is placed within a vise, the jaws of which are indicated at 11. The closing of the vise forces the jaws 9 together, forcing 75 the prongs into the belt and straightening the arms of the hook as shown in Fig. II.

By providing the diverging arms with the parallel portions 4 and disposing the prongs 5 at right angles to these parallel 80 portions, the prongs enter the belt straight, the tendency for them to be distorted being minimized. The prongs 5 are flattened at 5' preferably on opposed sides as illustrated, thereby providing clinching points which 85 are adapted to turn laterally to the longitudinal plane of the hook when the hooks are set, the direction of their clinching being thus predetermined, that is, they are clinched in a lateral direction thus gripping 90 the fibre of the belt at the side of the prong and a portion of the belt which is not broken or cut by the entrance of the prong, as is clearly shown in Figs. III and IV. Where the arms of the hook diverge from the right 95 thereof to the prongs as shown in the Conn Patent No. 779,587 there is a tendency for certain of the prongs to be distorted as by striking a portion of the belt more dense than other portions. By providing these 100 parallel portions 4 with the prongs disposed at right angles thereto this tendency is minimized. Further, the parallel portions engaging the jaws of the setting device, the tendency of the closing action of the jaws to 105 tilt the prongs is also minimized.

Having thus described my invention, what I claim as new and desire to secure by Letters Patent, is:

1. As an article of manufacture, a belt 110

- lacing hook having outwardly diverging arms of unequal length, the arms having parallel portions at their outer ends terminating in inwardly directed prongs disposed at right angles to the parallel portions, the adjacent sides of the prongs being flattened to taper the prongs and provide clinching points adapted when set to turn laterally relative to the longitudinal plane of the hook.
2. As an article of manufacture, a belt lacing hook having outwardly diverging arms of unequal length, the arms having parallel portions at their outer ends, the diverging portions being of the same length, said parallel portions terminating in inwardly directed prongs disposed at right angles to the parallel portions and conformed to provide clinching points adapted to turn laterally relative to the longitudinal plane of the hook.
3. As an article of manufacture, a belt lacing hook having outwardly diverging arms of unequal length, the arms having parallel portions at their outer ends, the angularly disposed portions being of the same length, said parallel portions terminating in inwardly directed prongs disposed at right angles to the parallel portions.
4. As an article of manufacture, a belt lacing hook having outwardly diverging arms terminating in parallel portions at their outer ends, such parallel portions ter-

minating in inwardly directed prongs disposed at right angles to the parallel portions and having opposed sides thereof flattened to provide laterally facing clinching points.

5. As an article of manufacture, a belt lacing hook having outwardly diverging arms of unequal length, the arms having parallel portions at their outer ends terminating in inwardly directed prongs disposed at right angles to the parallel portions.

6. As an article of manufacture, a belt lacing hook having outwardly diverging arms, the arms having parallel portions at their outer ends terminating in inwardly directed prongs disposed at right angles to the parallel portions.

7. As an article of manufacture, a loop-like belt lacing hook, the arms of which have inner diverging portions of the same length and outer parallel portions of unequal length terminating in inwardly projecting prongs disposed at right angles to the parallel portions.

8. As an article of manufacture, a loop-like belt lacing hook, the arms of which have inner diverging portions of the same length and outer parallel portions terminating in inwardly projecting prongs disposed at right angles to the parallel portions.

In witness whereof I have hereunto set my hand.

JAMES K. DIAMOND. [L.S.]
